UNITED STATES PATENT OFFICE.

EDWARD MORRIS, OF NEW BEDFORD, MASSACHUSETTS.

DESIGN FOR A THREADING-EYE FOR LOOM-SHUTTLES.

42,856.

Specification for Design.

Patented Aug. 6, 1912.

Application filed January 15, 1912. Serial No. 671,362. Term of patent 7 years.

To all whom it may concern:

Be it known that I, EDWARD MORRIS, a citizen of the United States, residing at New Bedford, in the county of Bristol and State of Massachusetts, have invented a new, original, and ornamental Design for a Threading-Eye for Loom-Shuttles; and I do hereby declare the following to be a full, clear, and exact description of the same, reference being had to the accompanying drawing, forming a part thereof, in which a perspective view of my design is shown.

I claim:

The ornamental design for a threading eye for loom shuttles, as shown.

In testimony whereof I affix my signature, in presence of two witnesses.

EDWARD MORRIS.

Witnesses:

JAMES MARGERISON,

JAMES WM. HOLDEN.
